UNITED STATES PATENT OFFICE.

IRA S. FISHER, OF MOLINO, MISSOURI.

METALLIC RAIL-TIE.

1,212,037.

Specification of Letters Patent.

Patented Jan. 9, 1917.

Application filed July 28, 1916. Serial No. 111,890.

To all whom it may concern:

Be it known that I, IRA S. FISHER, a citizen of the United States, residing at Molino, in the county of Audrain and State of Missouri, have invented certain new and useful Improvements in Metallic Rail-Ties; and I do hereby declare the following to be a full, clear, and exact description of the invention, such as will enable others skilled in the art to which it appertains to make and use the same.

This invention relates to railway roadbed construction of the type formed of concrete ballast and metallic rail ties, and the primary object of the invention is the provision of novel means which is adjustably carried by the tie and operatively engaging the concrete ballasts and adapted to normally hold the ties against longitudinal movement, and also adapted, when adjusted, to effect movement of the ties so as to admit of the ties being placed in proper position with relation to one another.

Another object of the invention is the provision of a novel type of tie anchoring means for preventing movement of the ties with respect to the ballast upon which they are supported.

Other objects will appear and be better understood from that embodiment of my invention of which the following is a specification, reference being had to the accompanying drawings forming a part thereof, in which:

Figure 1 is a top plan view of a portion of a roadbed and showing a rail tie constructed in accordance with my invention applied thereto, and showing the manner of connecting the rails to the tie. Fig. 2 is a section taken on the line 4—4 of Fig. 1, Fig. 3 is a section taken on the line 5—5 of Fig. 1, Fig. 4 is a longitudinal sectional view, taken through the tie, Fig. 5 is a perspective view of one of the plates designed to be positioned on the cushioning means, and forming a seat for one of the rails, Fig. 6 is a perspective view of one of the fastening elements for holding the rail fastening means in operative position on the tie.

Referring to the drawings in detail, the numeral 1 designates a concrete or cement ballast or roadbed, which has the base portion thereof wider than the top portion, and resting on the upper or top portion of the ballast is a metallic tie, designated, as an en-

tirety, by the numeral 2, and which tie is of inverted U-shape in cross section. The top wall, and upper edges of the side walls of the tie, are cut away at the opposite ends of the tie body and positioned within the tie and located at the opposite ends thereof are a pair of wooden blocks 3, the upper sides of which project a slight distance above the top wall of the tie body and have mounted thereon elongated plates 4. These plates 4 extend parallel with the top wall of the tie and form seats for the rails 5 of the track. Each of these plates 4 has its opposite ends bent and extended inwardly and engaged against the upper surface of the plate, as shown at 6, and the extended portion 6 on the inner end of the plate has the end thereof beveled, as shown at 7, and the portions 6 are held against the upper face of the portion 4 by suitable rivets 6a. 75 Rail fastening plates 8 lie on opposite sides of the base flanges of each of the rails 5 and have the edges opposing the base flanges of the rails provided with flanges which engage over the bases of the rails, and have their outer edges abutting the ends of the extensions 6. The innermost fastening plates 8 have their edges that oppose and engage the beveled ends 7 of the adjacent extensions 6 also beveled, so as to agree with the beveled ends of the extension 6. One of the side walls of the tie body is provided with vertical extensions 9, which are located adjacent the opposite ends of the wall and opposing the narrow end of the innermost rail fastening plate 8, and have openings therein which register with openings in the innermost plate 8. Bolts 10 extend through the openings in the innermost plate 8 and through the openings in the extensions 9, 95 and those ends of the bolts extended through the extensions 9 have lock nuts 11 mounted thereon and adjustable against the outer side of the extension, and adapted to cause tight engagement between the beveled portions on the adjacent extensions 6 and plates 8, so as to cause the plates 8 to tightly engage the rails. The inner ends of the plates 4 are spaced a slight distance above the upper wall of the tie, and plates 12, of insulation, are inserted beneath the inner ends of the plates 4 and the upper wall of the tie body. The inner ends of the plates 4 and the inner extensions 6 have registering openings 13, which register with the openings formed 110

in the upper wall of the tie body, for the reception of bolts 14, the upper ends of which are received by lock nuts 15, so as to secure the plates 4 in operative position. 5 The outer ends of the plates 4 and the outer extensions 6 formed thereon are provided with registering openings 16, for the reception of the shank 17 of a hook, the upper end of the shank having a lock nut 18 threaded thereon, and adjustable against the adjacent extension 6. Located at the opposite sides of the ballast 1 are upwardly converging bars 19, the upper ends of which are provided with eyes which receive the 10 bills of the hooks 17, and the lower ends of the rods 19 are provided with eyes which receive the outer ends of the rods 20, the inner ends of the rods 20 being embedded in the ballast or roadbed 1, and the outer 15 terminals of the rods 20 are bent downwardly, as shown at 21; so as to prevent detachment of the lower end of the rods 19 from the rods 20. These rods 19 and 20 provide anchors for preventing the upward 20 movement of the tie body during the passage of rolling stock over the rails. 25

Each of the blocks 3 has located therebeneath a pair of spaced plates 22, each of the said plates having integrally formed thereon 30 a pair of upwardly extending rods 23, which extend through openings in the adjacent blocks 3 and through the rail fastening plates 8, and the upper ends of the rods 23 are threaded, for the reception of lock nuts 35 24 which are adjustable against the upper sides of the plates 8, as shown more particularly in Fig. 4 of the drawings. Bolts 25 extend through the side walls of the tie body and through the blocks 3 and have lock nuts 40 26 adjustable on their threaded ends, so as to secure the bolts against accidental withdrawal from operative position.

A pair of eye bolts 27 have their shanks 45 extending through the opposite sides of the tie body 2, and the said eye bolts are located adjacent the opposite ends of the tie and are extended through the tie body in opposite directions, so that the respective heads thereof will be positioned on opposite sides of the tie body, as shown in Fig. 1. A pair of rods 50 28 are arranged respectively on opposite sides of the tie body, and are slidably received by the eyes in the heads of the bolts 27, and the outer ends of the rods 28 carry 55 depending heads 29, which are adapted to engage against the respective sides of the ballast 1, so as to prevent longitudinal movement of the tie when in operative position.

The opposite sides of the tie body are provided 60 with opposed slots 30, which are located at a medial point between the ends of the tie body and extending through the slots 30 are a pair of elongated plates 31. Each plate 31 has one end provided with an apertured head 32, the respective heads being lo-

cated, as shown in Figs. 1 and 3, on opposite sides of the tie body and receiving the inner ends of the rods 28, which inner ends of the rods are threaded and receive lock nuts 33 which are adjustable thereon and engage behind the heads 32. By adjusting the nuts 33, in one direction, the rods 28 are moved inwardly and the heads 29 brought into snug engagement with the adjacent sides of the ballast 1. When it is desired to move the tie longitudinally one of the nuts 33 is loosened and the other nut turned in a direction to cause the same to be engaged against the adjacent ear 32 and exert a pressure thereon which will result in movement being imparted to the tie body, and after the tie has been moved sufficiently the first-mentioned nut is then adjusted against the adjacent head 32, so as to hold the tie against movement. The opposed longitudinal edges of the plates 31 are provided with registering recesses which provide an opening for the reception of a bolt 34, the lower end of the bolt 34 being provided with an eye for the reception of a key 35, and the upper end of the bolt extends through an opening in the top wall of the tie body and is threaded for the reception of a lock nut 36, which is adjustable against the upper wall of the tie body. 95

It is evident that various changes might be resorted to in the construction, form and arrangement of the several parts without departing from the spirit and scope of my invention. Hence I do not wish to limit myself strictly to the structure herein described and claimed. 100

Having thus described my invention what I claim as new, is:

1. In a railway roadbed construction, the combination with a concrete ballast, of a tie mounted on the ballast, rods located at the opposite sides of the ballast and each having one end embedded therein, and its opposite end projecting beyond the ballast, second and vertically disposed rods located at the opposite sides of the ballast and having their lower ends provided with eyes for receiving the outer ends of the first-mentioned rods, and means associated with the opposite ends of the tie body for engaging the upper ends of the second-mentioned rods. 115

2. In a railway roadbed construction, the combination with a ballast having upwardly extending rods having the upper ends thereof provided with eyes, a rail tie mounted on the ballast, plates carried by the opposite ends of the tie and each having one end projecting beyond the adjacent end of the tie, and hooks depending from the projecting ends of the plates for engaging in the eyes in the upper ends of the rods. 120

3. In a railway roadbed construction, the combination with a ballast, and a rail tie mounted on the ballast, of rods adjustably 130

associated with the tie, and depending heads carried by the rods and operatively engaging the ballast, for the purpose specified.

4. In a railway roadbed construction, a ballast, a rail tie mounted on the ballast, rods positioned on opposite sides of the tie and adjustable thereon, means carried by the rods for engaging the ballast, plates carried by the tie, and apertured heads carried by the plates and located at the opposite sides of the tie and receiving the rods, and means adjustable on the rods and against the apertured heads for the purpose specified.
5. In railway roadbed construction, the

combination with a ballast, and a tie mounted on the ballast, upwardly extending rods located at the opposite sides of the ballast, means for connecting the lower ends of the rods to the ballast, plates carried by the tie, and means for connecting the upper ends of the upwardly extending rods to the tie plates.

In testimony whereof I affix my signature in presence of two witnesses.

IRA S. FISHER.
